UNITED STATES PATENT OFFICE.

EDWIN H. SHULER, OF LANSING, AND MAX C. SHULER, OF CHARLOTTE, MICHIGAN.

GAS BURNER.

1,421,591.

Specification of Letters Patent. Patented July 4, 1922.

Application filed August 11, 1921. Serial No. 491,536.

To all whom it may concern:

Be it known that EDWIN H. SHULER and MAX C. SHULER, citizens of the United States, residing at Lansing, county of Ingham, and Charlotte, county of Eaton, State of Michigan, respectively, have invented certain new and useful Improvements in Gas Burners, of which the following is a specification.

10 This invention relates to improvements in gas burners.

The main objects of this invention are:

First, to provide an improved burner having a pilot in which the burner is automatically turned on when an object is placed on the grid above the burner.

Second, to provide an improved gas burner having these advantages which is simple in structure and not likely to get out of repair in use, and further, one which may be substituted for gas burners now commonly used in gas stoves, gas furnaces and the like.

Further objects, and objects relating to structural details, will definitely appear from the detailed description to follow.

We accomplish the objects of our invention by the devices and means described in the following specification. The invention 30 is clearly defined and pointed out in the claims.

A structure which is a preferred embodiment of our invention is clearly illustrated in the accompanying drawing, forming a 35 part of this application, in which:

Fig. I is a plan view of a gas burner embodying the features of our invention, portions of a stove top or grid being broken away and also the gas supply connections.

40 Fig. II is a detail view mainly in vertical section on a line corresponding to line 2-2 of Fig. I.

Fig. III is a detail sectional view corresponding to that of Fig. II with the burner 45 valve open.

Fig. IV is an end view of the Bunsen tube of the burner.

In the drawing similar reference numerals refer to similar parts throughout the 50 several views.

Referring to the drawing, 1 represents the frame of a gas stove and 2 the top or grid thereof adapted to receive the article to be heated, such as a cooking utensil, 55 shown conventionally at 3 in Fig. III.

The main burner comprises the head 4

having radiating arms 5 provided with a plurality of jet orifices 6. The burner has a Bunsen tube 7 adapted to receive gas from the supply nipple 8 which is controlled by 60 the valve 9.

The Bunsen tube has an enlargement 10 at its outer end, a spider 11 being threaded into the tube and supporting the nozzle 12 which is threaded into a central bore in 65 the spider. The nozzle has a valve seat 13. The spider has openings 14 controlled by the shutter 15 rotatably mounted on the spider and secured in its adjusted positions by the screw 16 on the spider engaging the 70 slot 17 in the shutter.

The pilot burner 18 is carried by the pilot burner supply tube 19 which is mounted to reciprocate within an opening 20 in the wall of the burner at the rear of the Bunsen tube 75 and through the bridge-piece 21 projecting inwardly from the spider 11. This supply tube is provided with a valve 22 controlling the nozzle and thereby the delivery of gas to the main burner.

80 The supply tube has a central orifice 23 which, when the valve is closed, admits gas to the supply tube and supplies the pilot burner. The supply tube is provided with a conical packing member or valve 24 co-acting with the seat 25 surrounding the supply tube, thereby preventing the passage of gas when the same is turned on to the main burner, at the same time avoiding packing glands, which would make the structure 90 hard to operate.

A valve actuating member 26 is supported to reciprocate vertically through the main burner and is connected to the pilot burner by link 27, so that when the actuating member 95 is forced downwardly the main burner supply valve is opened. The actuating member is returned to its initial position by means of the weight 28 which is pivoted at 29 to engage the lower end of the stem of the actuating member 26. This weight is also adapted to hold the supply valve to its seat, the weight being provided with an arm 30 adapted to engage a lug 31 on the lower end of the pilot burner as shown in 105 Fig. II. The weight thus serves the double function of returning the actuating member to its initial position and of holding the supply valve to its seat, thus avoiding the use of return springs.

110 The nipple 8 is provided with a reduced or weakened portion 32 so that in the event

the parts are slightly out of alignment it will flex to accommodate such condition.

The parts of our improved valve are very simple and economical and easily assembled and are not likely to become inoperative or get out of repair.

Having thus described our invention, what we claim as new and desire to secure by Letters Patent, is:

- 10 1. In a structure of the class described, the combination of a grid, a main burner disposed below the grid and provided with a Bunsen tube and a nozzle delivering thereto having a valve seat at its inner end, a
15 pilot burner operatively associated with said main burner, a pilot burner supply tube carrying said pilot burner and mounted to reciprocate longitudinally in said Bunsen tube and through the wall at the inner end
20 thereof, said supply tube being provided with a packing valve coacting with a seat in the wall surrounding the tube, and with a nozzle valve at its outer end coacting with the valve seat in said nozzle to control
25 the delivery of gas to the main burner and an inlet opening registering with the nozzle opening when said nozzle valve is closed permitting the passage of gas to the pilot burner, a valve actuating member mounted
30 on said burner to reciprocate vertically and adapted to be actuated by an object placed on said grid, a link connecting said valve actuating member to said pilot burner, and a weight pivotally mounted on said main
35 burner for returning said valve actuating member to its initial position and provided with an arm engaging the pilot burner when the said actuating member is in its normal position whereby said nozzle valve
40 is held in its seat by said weight.
2. In a structure of the class described, the combination of a grid, a main burner disposed below the grid and provided with a Bunsen tube and a nozzle delivering
45 thereto having a valve seat at its inner end, a pilot burner operatively associated with said main burner, a pilot burner supply tube carrying said pilot burner and mounted to reciprocate longitudinally in said Bunsen
50 tube, said supply tube being provided with a nozzle valve at its outer end coacting with the valve seat in said nozzle to control the delivery of gas to the main burner and an inlet opening registering with the nozzle
55 opening when said nozzle valve is closed permitting the passage of gas to the pilot burner, a valve actuating member mounted on said burner to reciprocate vertically and adapted to be actuated by an object placed
60 on said grid, a link connecting said valve actuating member to said pilot burner, and a weight pivotally mounted on said main burner for returning said valve actuating member to its initial position and provided
65 with an arm engaging the pilot burner

when the said actuating member is in its normal position whereby said nozzle valve is held in its seat by said weight.

3. In a structure of the class described, the combination of a grid, a main burner 70 disposed below the grid and provided with a Bunsen tube and a nozzle delivering thereto having a valve seat at its inner end, a pilot burner operatively associated with said main burner, a pilot burner supply 75 tube carrying said pilot burner and mounted to reciprocate longitudinally in said Bunsen tube and through the wall at the inner end thereof, said supply tube being provided with a packing valve coacting with a seat 80 in the wall surrounding the tube, and with a nozzle valve at its outer end coacting with the valve seat in said nozzle to control the delivery of gas to the main burner and an inlet opening registering with the nozzle 85 opening when said nozzle valve is closed permitting the passage of gas to the pilot burner, a valve actuating member mounted on said burner to reciprocate vertically and adapted to be actuated by an object placed 90 on said grid, a link connecting said valve actuating member to said pilot burner, and a weight pivotally mounted on said main burner for returning said valve actuating member to its initial position. 95

4. In a structure of the class described, the combination of a grid, a main burner disposed below the grid and provided with a Bunsen tube and a nozzle delivering thereto having a valve seat at its inner end, a pilot burner operatively associated with said main burner, a pilot burner supply tube carrying said pilot burner and mounted to reciprocate longitudinally in said Bunsen tube, said supply tube being provided with a nozzle valve at its outer end coacting with the valve seat in said nozzle to control the delivery of gas to the main burner and an inlet opening registering with the nozzle opening when said nozzle valve is closed permitting the passage of gas to the pilot burner, a valve actuating member mounted on said burner to reciprocate vertically and adapted to be actuated by an object placed on said grid, a link connecting said valve actuating member to said pilot burner, and a weight pivotally mounted on said main burner for returning said valve actuating member to its initial position. 110

5. In a structure of the class described, 120
the combination of a grid, a main burner dis-
posed below the grid and provided with a
Bunsen tube and a nozzle delivering thereto
having a valve at its inner end, a pilot
burner operatively associated with said main 125
burner, a pilot burner supply tube carrying
said pilot burner and mounted to recipro-
cate longitudinally in said Bunsen tube
through the wall at the inner end thereof,
said supply tube being provided with a noz- 130

- zle valve at its outer end coacting with the valve seat in said nozzle to control the delivery of gas to the main burner and an inlet opening registering with the nozzle opening
- 5 when said nozzle valve is closed permitting the passage of gas to the pilot burner, said burner tube also having a packing valve coacting with a seat in the wall surrounding the tube when the nozzle valve is open, a
- 10 valve actuating member arranged to be actuated by an object placed on said grid, operating connections for said valve actuating member to said pilot burner tube, and a weight pivotally mounted on said main
- 15 burner for returning said valve actuating member to its initial position and adapted when in its normal position to hold said nozzle valve to its seat.
6. In a structure of the class described,
- 20 the combination of a grid, a main burner disposed below the grid and provided with a Bunsen tube and a nozzle delivering thereto having a valve seat at its inner end, a pilot burner operatively associated with said main
- 25 burner, a pilot burner supply tube carrying said pilot burner and mounted to reciprocate longitudinally of said Bunsen tube, said supply tube being provided with a nozzle valve at its outer end coacting with the valve seat
- 30 in said nozzle to control the delivery of gas to the main burner and an inlet opening registering with the nozzle opening when said nozzle valve is closed permitting the passage of gas to the pilot burner, a valve
- 35 actuating member arranged to be actuated by an object placed on said grid, operating connections for said valve actuating member to said pilot burner tube, and for returning said valve actuating member to its initial
- 40 position adapted to hold said nozzle valve to its seat.
7. In a structure of the class described,
- the combination of a grid, a main burner disposed below the grid and provided with a Bunsen tube and a nozzle delivering thereto
- 45 to having a valve seat at its inner end, a pilot burner operatively associated with said main burner, a pilot burner supply tube carrying said pilot burner and mounted to reciprocate longitudinally in said Bunsen
- 50 tube through the wall at the inner end thereof, said supply tube being provided with a nozzle valve at its outer end coacting with the valve seat in said nozzle to control the delivery of gas to the main burner
- 55 and an inlet opening registering with the nozzle opening when said nozzle valve is closed permitting the passage of gas to the pilot burner, said burner tube also having a packing valve coacting with a seat in the
- 60 wall surrounding the tube when the nozzle valve is open, a valve actuating member arranged to be actuated by an object placed on said grid, operating connections for said valve actuating member to said pilot burner
- 65 tube, and for returning said valve actuating member to its initial position adapted to hold said nozzle valve to its seat.
8. A gas burner comprising a Bunsen tube,
- 70 a spider threaded into the outer end of said Bunsen tube and having a threaded central bore and an inwardly projecting bridge-piece, a nozzle threaded into said spider and having a valve seat in its inner end, a valve member having a valve at its end reciprocating in said bridge piece to coact with said valve seat, an air shutter mounted on said spider, and a nipple threaded into said nozzle, said nipple having a weakened portion permitting flexing thereof.
- 75
- 80

In witness whereof, we have hereunto set our hands and seals.

EDWIN H. SHULER. [L.S.]
MAX C. SHULER. [L.S.]
